UNITED STATES PATENT OFFICE.

DANIEL S. BURKHART, OF SPOKANE, WASHINGTON.

ALARM SYSTEM FOR FIRE-ESCAPES.

1,171,088.

Specification of Letters Patent.

Patented Feb. 8, 1916.

Application filed March 5, 1915. Serial No. 12,287.

To all whom it may concern:

Be it known that I, DANIEL S. BURKHART, a citizen of the United States, residing at Spokane, in the county of Spokane and State 5 of Washington, have invented certain new and useful Improvements in Alarm Systems for Fire-Escapes, of which the following is a specification.

This invention relates to improvements in 10 alarm and lighting system and has to do more particularly with an improved system of this character which is especially adapted for use in connection with that type of fire escape apparatus which is actuatable or movable under the weight of a user, such for 15 instance as that disclosed in my co-pending application filed December 12, 1914, No. 876,995.

It is one of the objects of this invention 20 to provide a circuit, which is complete in itself, and which is not only independent of any circuit in the interior of the building but which is also disposed outside of the building and preferably mounted upon the 25 fire escape apparatus itself.

A further object is to equip or include in 30 the circuit, certain bells and electric lamps which are preferably disposed adjacent the building openings or doors or windows 35 along which the fire escape mechanism vertically extends so that in the event that only one person may be apprised of the existence 40 of a fire and mounts the fire escape mechanism to descend, such bells and lamps will then be energized to not only warn 45 other occupants but also to indicate, in darkness the position of the fire escape mechanism.

Other objects and features of the invention 50 will be more fully described in connection with the accompanying drawings and will be more particularly pointed out in and by the appended claims.

In the drawings:—Figure 1 is a view in 55 elevation of a building shown provided with the device of my invention applied to a fire escape mechanism constructed in accordance with my hereinbefore identified application, Fig. 2 is a sectional view on line 2—2 of Fig. 1, Fig. 3 is an enlarged fragmentary view of an improved gravity switch adapted to be actuated by the escape mechanism to close circuit when said mechanism is operated, Fig. 4 is a view looking in 60 the direction of the arrow shown in Fig. 3, Fig. 5 is a view similar to Fig. 3 showing

the parts in different positions, Fig. 6 is a diagrammatic view of the circuit.

Like characters of reference designate 60 similar parts throughout the different figures of the drawings.

As illustrated, 1 designates the side of a building in which superposed building openings such as windows 3 and 4, are provided. Adjacent the windows I have shown platforms 3' and 4' to be used by occupants 65 escaping through the windows prior to mounting the escape mechanism. Said mechanism, like my prior application, is embodied in the form of an endless mechanism 70 or carrier 5 and 6 having foot treads 7 suspended by pivots 8 and supporting lines 9. Suitable hand holds 10 are positioned in a manner to be grasped by the hands of the user. The upper bights of said carrier are 75 shown trained about wheels 11 mounted upon a shaft which is journaled in bearings 12 and 13. The bearing 13 may have incorporated therein a governor, for controlling the rate of speed of the fire escape mechanism, under gravity action due to the weight 80 of the user, such mechanism being exemplified for instance in the device disclosed in my copending application filed December 12, 1914, Serial No. 876,995. The lower 85 bights of the carriers 5 and 6 are trained about wheels 14, mounted upon a shaft 15, journaled in suitable bearings 16. The frame work of the fire escape mechanism may include a pipe or conduit 17 for containing the electrical wires comprising the 90 circuit and also for supporting exterior guiding lamps 18, to guide occupants in their approach to the fire escape mechanism 95 from the platforms 3 and 4. Alarm devices such as electric bells 19, are disposed interiorly of the building and the conduit 17 has branches 20 which extend through the wall of the building 1 so as to protect the wires leading to the bell. 100

Referring to the circuit shown in Fig. 6, 21 designates a source of current which may be disposed in any desired position exteriorly of the building and to one pole of which is connected a conductor 22 which is 105 branched at 23, 24 and 25, for connection with the bells 19. The other pole of said source of current is connected with a conductor 26, which latter is connected at 27 with one terminal of a circuit closing switch. 110 A conductor 28 is shown connected at 29 with the other terminal of the circuit clos-

ing switch and is also connected at 30, 31 and 32 with the bells 19 to complete circuit therewith. A manually operable switch 33, 5 may be provided, as shown in Fig. 6, for the usual purpose. A conductor 34, is connected at 35 with the same switch terminal that the conductor 28 is connected with and is also provided with branch connections 36, 37 and 38 with the lamps 18. The lamps 10 18 are connected by conductors 39, 40 and 41 with conductor 22. A manually operable switch 42 may be interposed in conductor 34.

My improved circuit closing switch is 15 mounted upon a bracket 43, of conducting material, which in turn is secured to platform 4. The bracket 43 is insulated from platform 4 by insulating material 44. A spring terminal 45 is mounted upon a block 20 of insulating material 46 and is connected with conductor 26, at 27. A swinging switch arm 47 is mounted on the bracket 43, at 48, to swing about a fixed axis and switch arm 47 is provided with a weight 25 49 which normally acts to swing said arm into a circuit closing position into engagement between the forked ends 50, of spring contact 45, after the switch arm has been thrown off from a substantially vertical position shown in Fig. 3. The switch arm 47 is provided with an insulated backing 51 for engagement with an actuating member 52, mounted upon shaft 15, which latter is actuated by the escape mechanism. After 30 35 the escape mechanism has been used it will be adjusted so that the revolving actuating member 52 will be disposed in the position shown in Fig. 3. The switch arm 47 will be adjusted off from a vertical dead center 40 so that the weight 49 will act to hold the arm 47 in the position shown in Fig. 3, against actuating member 52. Immediately after a user has mounted the escape, its mechanism will begin to rotate actuating member 52 and the latter will throw arm 47 off from a dead center position so 45 that the weight 49 will carry said arm into electrical engagement with forked ends 50 so as to close circuit and energize the lamps 50 and bells. These alarm devices will thereafter continuously operate until the switch arm 47 has been manually retracted out of

engagement with forked ends 50, irrespective as to whether or not the fire escape mechanism is continuously operated by 55 subsequent users.

It is believed that the advantages and utility of my invention will be fully understood from the foregoing description, and while I have herein shown and described 60 one specific form of my invention, I do not wish to be limited thereto except for such limitations as the claims may import.

I claim:

1. In an alarm and lighting system for 65 fire escapes, a fire escape mechanism comprising endless user supporting means, a circuit disposed along said mechanism, alarm and lighting devices in said circuit distributed along said mechanism, a circuit closing switch means for closing said circuit, and a device rotated by said endless means for actuating said switch means to close said circuit, substantially as described.

2. In an alarm or protecting system for 75 fire escapes, a fire escape mechanism movable under the weight of a user, an electric circuit, warning or protecting devices in said circuit and disposed along the building area protected by said mechanism, a 80 switch for closing said circuit including a gravity movable weighted arm, and means rotatable upon movement of said mechanism for shifting said arm into a gravity acting position, substantially as described. 85

3. In an alarm and lighting system for 90 fire escapes, a fire escape mechanism movable under the weight of a user and extending vertically along and outside of a building to be protected, a conduit extending along said mechanism, a circuit comprising 95 conductors disposed in said conduit, electric lamps mounted on said conduit and connected with said circuit, bells connected with said circuit, and means operated by said mechanism for closing said circuit, substantially as described.

In testimony whereof I affix my signature in presence of two witnesses.

DANIEL S. BURKHART.
